J. SCHMITZ.

DYEING APPARATUS.

APPLICATION FILED MAY 31, 1913.

1,105,845.

Patented Aug. 4, 1914

UNITED STATES PATENT OFFICE.

JOSEPH SCHMITZ, OF PHILADELPHIA, PENNSYLVANIA, ASSIGNOR, BY MESNE ASSIGNMENTS, TO UNIFORM DYEING MACHINE COMPANY, A CORPORATION OF NEW JERSEY.

DYEING APPARATUS.

1,105,845.

Specification of Letters Patent.

Patented Aug. 4, 1914.

Application filed May 31, 1913. Serial No. 770,977.

To all whom it may concern:

Be it known that I, JOSEPH SCHMITZ, a citizen of the United States, residing at Philadelphia, in the county of Philadelphia and State of Pennsylvania, have invented a certain new and useful Improved Dyeing Apparatus, of which the following is a specification.

The principal object of the present invention may be said to reside in the providing of an improved dyeing apparatus, in which the goods to be dyed rest upon spaced, horizontal, superimposed perforated shelves, through which is caused to circulate stock liquor or dye, first, upwardly in a continuous cycle and then downwardly in a continuous cycle, whereby the texture of the goods being dyed is caused to remain in unrumpled and unroughened condition and is uniformly and evenly impregnated with the dye.

A further object of the present invention resides in the providing of a novel arrangement and construction of parts for attaining the above result.

A still further object of the present invention resides in the providing of apparatus, whereby when the goods have been dyed, the tub or tank containing the goods may be readily emptied of stock liquor or dye and a continuous cycle of clean water circulated upwardly through the goods, for cleansing purposes, the dirty water being drained off meanwhile from the tank top.

A still further object of the present invention is to provide a novel arrangement and construction of parts for effecting this result.

Other and further objects of the present invention reside in the providing of a novel combination, arrangement and construction of parts of simple and inexpensive manufacture, whereby textile fabrics may be more efficiently and expeditiously dyed and washed than by present methods.

With these and other objects in view, the invention consists of the improvements hereinafter described and finally claimed.

The nature, characteristic features and

scope of the invention will be more fully understood from the following description taken in connection with the accompanying drawings forming part hereof and in which:

Figure 1, is a view in elevation of the improved dyeing apparatus of the invention, 55 Fig. 2, is a top or plan view, upon a reduced scale, of the dye tub or tank shown in Fig. 1, Fig. 3, is a view in vertical section taken upon the line 3—3 of Fig. 2, Fig. 4, is a fragmentary view in section, drawn 60 to an enlarged scale, and illustrating details of construction shown in Fig. 3, and Fig. 5, is a fragmentary view, in plan, of one of the removable perforated plates shown in Figs. 2, 3, and 4. 65

In the drawings there is disclosed a specific embodiment of the invention constructed in accordance with the mode best known to me at this time for practising the invention. Obviously, details of construction 70 and general arrangement of parts may be varied to accomplish the same purposes and I wish it understood that such variations and arrangement of parts come within the scope of the present invention. The tub or 75 tank for containing the goods to be dyed, is designated 10, and for illustrative purposes is shown as comprising a wooden structure divided into compartments 11, and 12, of different sizes by means of a vertical partition 13. The compartment 11, which is relatively large and is a goods receiving chamber is provided upon its side walls with spaced elongated, angle irons 14, which extend longitudinally of the compartment and 80 are adapted to receive a series of removable, perforated, metallic plates 15. These plates 85 15, as shown are comparatively narrow and are adapted to be arranged crosswise of the compartment side by side in abutting position, to form shelves, see Fig. 2. Each plate is provided at its opposite ends with a temporary securing medium shown in the drawings, as being a shiftable bolt 16, which 90 bolts are adapted to be accommodated by 95 apertures 17, in the side walls of the tub or tank 10, see Fig. 4. By such construction, the plates 15, may be readily fitted and tem-

porarily secured in place in the compartment 11, of the tub or tank 10, and as readily removed therefrom. The plates 15, are also preferably provided with means whereby the same may be readily lifted from said compartment. As shown, hand grips 18, secured above or adjacent the bolts 16, may be conveniently used. Within the compartment 11, of the tub or tank 10, beneath the lowermost shelf and resting upon the bottom of the tank is a union joint 19, branching from which are a plurality of short pipe sections 20, slotted as at 21, to form a liquid distributer. The union joint 19, connects with a pipe 22, which extends up through the bottom of the tank 10, for a purpose to be presently described. The tub or tank 10, conveniently at one side thereof, is provided with a waste water overflow conduit 23, having communication as at 24, see Figs. 2, and 3, with the top of the compartment or chamber 11, which conduit 23, may lead to a sewer connection or other desired point. This conduit 23, is utilized when goods are being washed after the dyeing process, at which time a movable gate 25, shown in the drawings as having hinged relation with the top of the partition 13, is used in conjunction with said conduit, as will hereinafter be described.

A description will now be given of the means utilized for circulating dye first upwardly through the perforated plates 15, and then reversely downwardly through said plates.

Located between the tub or tank 10, and the stock liquor or dye reservoir 26, is a centrifugal pump 27, operable by any suitable medium. As shown in the drawings, the driving shaft 28, of the centrifugal pump is provided with fast and loose pulleys 29, and 30, belt 31, being present for driving purposes. Leading from the inlet end 32, of the pump 27, is a horizontal pipe 33, connecting with the compartment 12, of the tank 10, which compartment is relatively small and may be termed an auxiliary chamber. Leading from the outlet end 34, of said pump is a vertical pipe 35, which connects with a horizontal pipe, the branch 36, of which has a valve 44, and leads to the top of the stock liquor or dye reservoir 26, and the branch 37, of which terminates in relatively vertical sub-branches 38, and 39. Of these sub-branches 38, and 39, pipe 38, connects with the pipe 33, and pipe 39, connects with the pipe 22, which pipe 22, in turn, is branched from the pipe 33, and connects with the union joint 19, within the compartment 11, as hereinbefore described. At the juncture point of the branches 37, 38, and 39, a three-way valve 40, is present and at the juncture point of the pipes 22, and 33, a three-way valve 41, is present. Leading from the reservoir 26, and connect-

ing with the pipe 33, adjacent the inlet end of the pump 27, is a pipe 42, having a valve 43. It will thus be seen that the three-way valve 41, as shown in Fig. 1, is located at a point upon the pipe 33, intermediate of the pipe 42, and the pipes 38, and 39. Leading from the branch pipe 36, at a point intermediate the valve 44, and the outlet connection 35, of the pump 27, is a waste water discharge pipe 45, provided with a valve 46. This pipe 45, may lead to a sewer connection or other suitable point.

The goods to be dyed being in position, upon the shelves within the compartment 11, the centrifugal pump 27, is operated and the various valved connections adjusted, so that stock liquor or dye from the reservoir 26, is drawn through the pipe 42, to and through the pump 27, and forced out through the outlet connection 35, to branch pipe 37, thence downwardly through pipe 39, to and through pipe 22, and into the compartment 11, of the tub or tank 10, at which point said dye is distributed evenly over the base area of compartment 11, and is forced upwardly through the superimposed, perforated, plates 15, and through the goods contained thereon. During this operation the overflow stock liquor or dye passes over the top of the partition 13, into the auxiliary compartment 12, from which point it passes back to the inlet end 32, of the centrifugal pump 27. By this arrangement of parts when the compartment 11, has been sufficiently filled, the valve 43, of the pipe 42, may be closed and a continuous cycle of liquid dye be circulated through the goods being dyed, steam being injected into the auxiliary compartment 12, of the tank 10, by means of the pipe 47, for keeping the liquid dye heated during the dyeing operation. After the stock liquor or dye has thus been circulated for a sufficient length of time, the three-way valves 40, and 41, and the other valves are so adjusted that the dye in the compartment 11, of the tank 10, is caused to be drawn or sucked through pipe 22, to pipe 33, through the pump 27, and then forced out through the connection 35, to the branch pipe 37, and from thence through pipes 38, and 33, to the compartment 12, of the tub or tank 10, and over the top of the partition 13, to the compartment 11, and is then caused to be drawn or sucked down through the apertured plates 15 to the pipe 22, and to the pump 27, thus completing a continuous cycle of dye and in effect recirculating the dye previously forced through the tub or tank in an opposite vertical direction. This last operation being continued until the goods are thoroughly dyed, the three-way valve 40, is adjusted to shut off pipes 38, and 39, and the other valves adjusted so that the dye within the tub or tank, is drained out 130

through the pipes 22, and 33, direct to the pump 27, and forced through pipe 36, back into the reservoir 26.

The goods are now ready to be washed. 5 For this purpose the valve of the water supply pipe 48, is opened thereby permitting clean water to empty into the auxiliary compartment 12, of the tub or tank 10, from which point it is drawn or sucked by 10 the pump 27, through pipe 33, and exhausted through pipes 35, 37, 39, and 22, to the bottom of the tub or tank, the valves 40, 43, and 44, having been previously regulated to permit of such circulation. The gate 25, 15 of partition 13, is now lifted to the position shown in Fig. 3, in which position it may be retained by means of shiftable bolts 49, similar to those disclosed in Fig. 4. The gate 25, in elevated position extends the 20 partition 13, so that the top thereof is above the inlet opening 24, of the waste water conduit 23. Thus the conduit 23, will readily drain off dirty water and scum at the tank top whereby clean water is constantly supplied to the tub or tank 10, and the dirty 25 water drained off. When the goods are sufficiently washed, the valve 46, of the pipe 45, is opened, the three-way valve 40, closed and the water within the tank 10, is exhausted 30 through the pipes 22, and 33, pump 27, pipe 35, branch pipe 36, and pipe 45, to a sewer connection or other suitable point. The goods upon the shelves within compartment 11, thus dyed and washed may now be 35 removed and in this connection, it is to be noted that the commercial value thereof is enhanced by reason of the fact that the goods are uniformly and evenly dyed; the texture of the fabric is not roughened; the 40 goods themselves are not rumpled and because they are thoroughly and efficiently washed. It may be remarked that these results are attained chiefly because the goods are retained between the shelves in relatively 45 fixed position and the dye and water forced therethrough in contradistinction to having the goods whirled or circulated through the dye and water.

What I claim is:

- 50 1. In dyeing apparatus, a dye tub or tank divided into separate compartments, one of said compartments being provided at its bottom with a liquid distributor, which distributor and the bottom of the other compartment have piped connection with a source of liquid supply and a series of spaced, horizontal, superimposed, perforated shelves fitted to the compartment having the distributor therein.
- 60 2. In dyeing apparatus, a dye tub or tank, spaced, horizontal, superimposed, perforated shelves for the goods to be dyed, and a pipe having right angled branches located below the lowest shelf, said branches 65 having lateral apertures so that dye liquor

escaping through said apertures, will pass up through the entire mass of material supported by the shelves.

3. In dyeing apparatus, a dye tub or tank, perforated shelves located one directly above the other, detachably secured directly to the dye tub or tank of which the uppermost shelf constitutes a covering shelf and the remaining shelves, goods receiving shelves, and means for circulating dye liquor in either direction through said shelves. 75

4. Dyeing apparatus comprising a dye tub or tank consisting of a generally rectangular structure divided into separate compartments one of which compartments is provided at its bottom with a liquid distributor which distributor and the bottom of the other compartment have piped connection with a source of liquid supply and a series of superimposed horizontally spaced apertured shelves fitted to the compartment having the distributor therein. 80

5. Dyeing apparatus comprising a dye tub or tank consisting of a generally rectangular structure divided into separate compartments of which one is relatively large and the other relatively small the larger compartment having therein at its bottom a liquid distributor having piped connection with a source of liquid supply and the smaller compartment having piped connection at its bottom with said source of liquid supply, spaced superimposed plate supports upon the tank walls within the large compartment and a series of perforated plates 90 removably fitted to said supports. 95

6. Dyeing apparatus comprising a dye tub or tank consisting of a generally rectangular structure divided by a vertical partition into a small and a large compartment of which the smaller of said compartments has at its bottom piped connection with a source of liquid supply and of which the other compartment constitutes a goods receiving chamber and has therein at its bottom, a liquid distributor which has piped connection with a source of liquid supply, a series of spaced horizontal superimposed apertured plates within said chamber, a waste overflow conduit communicating with the goods receiving chamber at its top and a movable gate for the vertical partition capable of being shifted so that the top thereof may be in a plane higher than that of the conduit inlet. 105

7. Dyeing apparatus comprising a generally rectangular dye tub or tank divided by a vertical partition into a relatively large goods receiving chamber and an auxiliary chamber of smaller dimensions, of which the former chamber has therein at its bottom branched and apertured pipes forming a liquid distributor having piped connection with a source of liquid supply and of which the latter chamber has piped connection at 115 120 125 130

its bottom with the same source of liquid supply, a series of removable spaced superimposed apertured shelves within said goods receiving chamber said shelves having interlocked relation with the walls thereof, a waste overflow conduit communicating with the latter chamber adjacent its top, a shiftable gate for the vertical partition capable of being moved to bring the height of said

partition in a plane above the conduit opening and means for delivering a cleansing fluid to said auxiliary chamber.

In testimony whereof, I have hereunto signed my name.

JOSEPH SCHMITZ.
